US00D700736S

(12) **United States Design Patent**
Schuyler

(10) **Patent No.:** **US D700,736 S**
(45) **Date of Patent:** **** Mar. 4, 2014**

(54) **DECORATIVE ELEMENTS**

(71) Applicant: **Swarovski Lighting, Ltd.**, Plattsburgh, NY (US)
(72) Inventor: **Andrew Schuyler**, Colchester, VT (US)
(73) Assignee: **Swarovski Lighting, Ltd.**, Plattsburgh, NY (US)

(**) Term: **14 Years**

(21) Appl. No.: **29/448,653**

(22) Filed: **Mar. 13, 2013**

(51) **LOC (10) Cl.** **26-99**
(52) **U.S. Cl.**
USPC **D26/113**

(58) **Field of Classification Search**

USPC D26/154, 155, 152, 142, 151, 153, 113, D26/119, 122, 123, 124, 138, 139, 145, 148, D26/146, 147, 121, 125, 126, 74, 75, 144, D26/150, 141, 118, 120, 128, 129, 132, 135, D26/71, 72, 85, 62, 65, 64, 24, 1, 2, 66, 67, D26/68, 73, 89, 86, 87, 88, 25, 26, 61, 63, D26/69, 76, 77, 78, 79, 90, 91, 84, 92, 49, D26/37, 38, 39; D13/179, 180, 171, 173; D11/90, 121, 89; 63/32; 362/253, 257, 362/333, 326, 169, 187, 307, 327, 308, 309, 362/362, 337, 208, 158; 16/442; 359/708, 359/641, 726; D6/581; D9/452, 435, 453, D9/443

(57) **CLAIM**

The ornamental design for decorative elements, as shown and described.

DESCRIPTION

This application contains subject matter which is related to the subject matter of commonly assigned and co-filed United States Design patent application Ser. No. 29/448,655, entitled "Light Fixture" by Andrew Schuyler, which is hereby incorporated in its entirety herein by reference.

FIG. 1 is a perspective view of an decorative elements in accordance with the new design;

FIG. 2 is a front elevational view thereof;

FIG. 3 is a left side elevational view thereof;

FIG. 4 is a right side elevational view thereof;

FIG. 5 is a rear elevational view thereof;

FIG. 6 is a top view thereof; and,

FIG. 7 is a bottom view thereof.

The broken lines in the figures illustrate portions of the decorative elements and form no part of the claimed invention.

1 Claim, 5 Drawing Sheets
